UNITED STATES PATENT OFFICE

ANDREW F. HOWE, OF UNIVERSITY CITY, MISSOURI

SAND RAMMING MACHINE

Application filed August 22, 1929. Serial No. 387,581.

This invention relates to ramming machines and has special reference to machines for use in ramming and compacting sand.

An object of the invention is to provide a machine for use in ramming sand in molds and the like, comprising mechanism for compacting and conveying the same to the ramming head, in combination with a rotary ramming head operating at rapid speed to separate bodies of the compacted sand and throw the separated bodies with great force into the mold so as to ram the sand in the mold in position for use.

Another object of the invention is to provide a machine of the character and for the purpose mentioned, having movable carriages for supporting the compacting and ramming mechanism and for moving the compacting and ramming mechanism to different positions above the mold so that the sand can be rammed into all parts of the mold.

Another object of the invention is to provide a machine of the type and character mentioned capable of being applied to other uses as well as to the work of ramming sand in molds.

Other objects will appear from the following description, reference being made to the accompanying drawings in which—

Fig. 1 is a side elevation of a machine embodying my present invention, the supports for the conveying and compacting mechanisms and devices being omitted.

Fig. 2 is a vertical longitudinal sectional view enlarged with respect to Fig. 1, the lower truck or carriage being omitted.

Fig. 3 is a plan view showing the intermediate or laterally movable carriage mounted on the lower carriage or truck.

Fig. 4 is a plan view of the upper or longitudinally movable carriage which supports and operates the ramming mechanism and which is mounted on the intermediate or laterally movable carriage shown in Fig. 3.

Fig. 5 is an end elevation of the ramming head, the end wall of the housing thereof being omitted.

Fig. 6 is a vertical cross sectional view of the compacting and conveying mechanism

whereby the sand is compacted and conveyed to the ramming head.

Fig. 7 is an end elevation of the intermediate or laterally movable carriage that is shown in plan view in Fig. 3.

Fig. 8 is an enlarged detail view showing a portion of the conveyer in which the sand is compacted and by which the sand is conveyed to the ramming head.

Fig. 9 is a sectional view of the support and the actuator for the conveyer.

Fig. 10 is an end elevation of one of the conveyer units.

Fig. 11 is a side elevation of one of the conveyer units.

Fig. 12 is a view showing the end of one of the conveyer units opposite the end shown in Fig. 10.

Fig. 13 is a side elevation of the complete compacting and conveying mechanisms and their supports.

Fig. 14 is a detail sectional view of the impeller device on the ramming head.

Fig. 15 is a plan view showing the impeller device on the ramming head.

Fig. 16 is a detail view showing the mechanism for operating the laterally movable reciprocating carriage back and forth over the molds.

Fig. 17 is a detail view showing a tensioning device, one of which is used in connection with the conveyer and one of which is used in connection with the compacting device.

Fig. 18 is a side elevation of a portion of one of the supports showing the slot through which extends the adjustable shaft for the conveyer and the similar shaft for the compacter.

The truck or supporting carriage for supporting and moving this machine longitudinally to different positions for operation is mounted on axles 1 supported by wheels 2 operating along a track comprising rails 3. The rails 3 constituting the track may be on opposite sides of a row or rows of molds into which the sand is to be rammed by the machine. The truck or carriage frame comprises longitudinal side members 4 rigidly connected at their ends by cross members 5.

The side members 5 constitute supports for rails 6 laid transversely of the truck and of the rails 3. The supporting carriage of the truck may be moved along the rails 3 from one mold to another.

5 The machine as shown comprises an intermediate or laterally movable carriage mounted on wheels 7 supported for operation along the rails 6. Two of the wheels 7 are attached to an axle 8 which supports a carriage side frame member 9; and another pair of wheels 7 are mounted on axle members 10 supporting a carriage side frame member 11. The side frame members 9 and 11 are rigidly connected at one end by a frame end member 12, and near the opposite end by a rigid frame end member 13. It is now clear that the lower carriage or truck may be moved longitudinally along the track 3 to position the machine over the respective molds successively, and that the intermediate carriage is movable back and forth along the track 6 transversely of the respective molds so as to cause the ramming head to ram the sand into every part of said molds.

25 A motor 14 is mounted on a base 15 rigid with the side frame member 9 and has its shaft equipped with a worm 16 (Figs. 3 and 16) engaging a worm device 17 on the axle 8. Thus the motor 14 may be caused to rotate the axle 8 and thereby the wheels 7 that are attached to the ends of said axle in order to move the intermediate or transversely movable carriage back and forth in opposite directions along the track 6. For the motor 14 may be of familiar type of motor that is capable of operation, or the device may include other familiar reversing mechanism for rotating the shaft 8 in opposite directions by operation of said motor. For illustrative purposes the motor 14 is mentioned as capable of rotation in both directions.

30 The upper or longitudinally movable carriage which supports the compacting and conveying mechanism comprises a side member 18 having a laterally extended flange 19 mounted in a horizontal groove 20 in the inner side of the carriage side member 9 (Fig. 6); and a longitudinal side member 21 having a laterally extended flange 22 operating in a longitudinal groove 23 in the inner side of the longitudinal carriage side member 11. Near one end the side members 18 and 19 are rigidly or integrally connected by a base plate 24 and by a raised platform 25. A pair of parallel spaced longitudinal bars 26 are formed integral with the base 24 and the raised platform 25 and projecting forwardly between the planes of the frame side member 18 and 21, but are somewhat above the horizontal plane of said frame side members 18 and 21 because the bars 26 are above the raised platform 25. An electric motor 27 is supported by and below the platform 25 and drives a shaft 28, to which a pinion 29

is attached (Fig. 6). The pinion 29 is in mesh with a gear 30 which is rigid on a rotary short shaft 31. The outer end of the shaft 31 is rotatively supported by the frame side member 18 and the inner end of said shaft 31 is rotatively supported by a part 32 depending from the under side of the raised platform 25. A pinion 33 is rigid on the shaft 31 and meshes with a horizontal rack 34 supported for sliding movements on supporting arms 35 in rigid connection with the side member 9 of the intermediate and transversely movable carriage. The ends of the rack 34 project for sliding movements through spring sockets 36 rigid with the carriage side frame member 9. Coil springs 37 encircle the ends of the rack 34 within the spring sockets 36 and have their outer ends bearing against the outer end walls of said sockets and their inner ends bearing against abutments 38 rigid with the rack 34 (Fig. 3). The springs 37 yieldingly hold the rack 34 in its intermediate or starting position but yield to permit limited longitudinal movement of said rack in both directions from and to its intermediate or starting position. Because the rack 34 is capable of movement to a limited extent only, it is clear that operation of the motor 27 will rotate the pinion 33 which is in mesh with said rack 34 and move the upper carriage longitudinally with respect to the lower carriage which is transversely with respect to the directions of movement of the intermediate carriage on which the upper carriage is mounted. The teeth on the rack 34 do not extend to the spring sockets 36. When the upper carriage reaches the position in its movement toward either end of the intermediate carriage in which the pinion 33 is at the end of the teeth of the rack 34, said pinion 33 may continue to rotate without moving the upper carriage further toward the end of the intermediate carriage. That is to say, when the pinion 33 reaches the end of the teeth on the rack 34, this gearing, comprising said pinion 33 and said rack 34, is ineffective to move the upper carriage further in the direction in which it had been moving. The springs 37 act to permit slight movement of the rack 34 as the pinion 33 continues to rotate. Thus, the springs 37 maintain the rack 34 in the relationship to the pinion 33 such that when the motor 27 is reversed to rotate the pinion 33 in the reverse direction from that in which said pinion 33 had been rotating, said pinion 33 will cooperate with the rack 34 to move the upper carriage in the reverse direction, which is toward the opposite end of the intermediate carriage. For, this driving mechanism for the upper carriage never moves said upper carriage to a position in which the pinion 33 and the rack 34 are incapable of co-operation to reverse the direction of movement of the upper carriage. Since the mo-

tor 27 is of the type that is capable of operation in either direction, it is now clear that said motor may be operated to move the upper or longitudinally movable carriage longitudinally in both directions along the intermediate or laterally movable carriage.

The ramming head is enclosed within in a housing comprising an inner end wall 39 rigid with the ends of the carriage side members 18 and 21 and with the ends of the bars 26 (Figs. 2 and 4); and outer end wall 40 of the same shape as the end wall 39; and a curved wall 41, the ends 42 and 43 of which extend downwardly in connection with downwardly extended portions 44 and 45 of the end walls 39 and 40 to form a chute or nozzle through which the sand is thrown downwardly. A shaft 46 is journaled for rotation in bearings 47 supported between the bars 26, and projects concentrically into the ramming head housing just described. A ramming head wheel 48 is attached to the end of said shaft 46 within the ramming head housing. The housing wall 41 curves concentrically with the axis of said shaft 46 and said wheel 48 through about 300 degrees, more or less. The wall portions 42, 43, 44, and 45, form a chute or nozzle through which the compacted sand is discharged by the ramming head. A thrower or impeller for the ramming head is attached to the wheel 48 and comprises a pair of spaced side walls 49 and an inclined end wall 50. This impeller is rigidly and detachably clamped against the periphery of the wheel 48 and against an abutment 51 by a clamping device 52 (Fig. 14). The shaft 46 is rotated in a counter-clockwise direction, as shown in Fig. 5, by a motor 53 rigidly secured on the base plate 24 of the upper longitudinally movable carriage.

Two supporting members 54 are rigid on the bars 26 and support two parallel channel bars 55. Spaced below the bars 55 are two rigid parallel bars 56. These bars 55 and 56 constitute guides and supports for the conveyer which conveys the compacted sand to the ramming head. A transverse shaft 56^a projects through slots 56^b near the rear ends of the bars 55 and supports 54 and are journaled in movable bearings 56^c (Figs. 13 and 17). The bearings 56^c are held on supporting brackets 56^d by clamping bolts 56^e extending through slots 56^f in said bracket. The bearings 56^c are held in different adjusted positions along the brackets 56^d by set screws 56^g. These adjustable bearings constitute means for tightening the conveyer. A shaft 57 is supported near the front ends of the frame members 54 and has attached thereto a sprocket wheel 58 which is engaged by a sprocket chain 59 driven by a sprocket wheel 60. The sprocket wheel 60 is attached to a shaft 61 having rigid thereon a worm gear 62 meshing with a worm 63 on the shaft 46. The shaft 56^a has attached thereto a wheel 64 having

peripheral shoulders 65 and constituting a sprocket wheel for the conveyer. The shaft 57 has a similar sprocket wheel 66 attached thereto.

The conveyer comprises a series of links 67 pivotally connected to form an endless chain by axle pins or rods 68, having on their ends rollers 69 operating upon the upper and lower surfaces of the bars 55 and upon the upper surfaces of the bars 56. This chain is mounted upon the sprocket wheels 64 and 66 and is driven by the shaft 46 through the connections leading to the shaft 57, as described. Each link 67 supports a section of the conveyer. Each conveyer section includes an arcuate bottom wall portion 70, an approximately vertical side wall portion 71, and a flaring side wall portion 72. During the time that the conveyer is passing along the upper sides of the bars 55 the ends of the respective conveyer sections are in abutting contact, as clearly shown in Fig. 2 of the drawings. Thus, from end to end of the bars 55, the conveyer sections form a channel or troughlike conveyer moving toward the ramming head 48. The sand is delivered into this conveyer through and from a hopper 73 as the conveyer passes below the open bottom of said hopper. The opening at the bottom of the hopper 73 is approximately equal to the width of the inside of the conveyer, that is, the width at the opening of the bottom of the hopper 73 is approximately equal to the distance between side wall portions 71 and 72 of the conveyer. This endless conveyer may be properly tensioned by adjustment of the bearings 56^c, as described.

A pair of shafts 74 and 75 are rotatively supported above the conveyer by frame members 75^a. The shaft 75 is journaled in adjustable bearings 75^b constructed, arranged, and adjusted just as are the bearings 56^c, so that further specific description is not needed. A sprocket wheel 76 is attached to the shaft 74 and a peripherally notched wheel 77 is attached to the shaft 75. The shaft 74 is driven by a sprocket chain 78 engaging a sprocket wheel 79 on said shaft 74 and also engaging a sprocket wheel 80 on a shaft 81 which is driven from the shaft 61 by gearing 82 (Fig. 4).

An endless compacting device is operated by the sprocket wheel 76, and comprises an endless series of presser or compacter plates 83, having their adjacent ends pivoted together by pivot rods 84 which are engaged by the sprocket wheel 76 and which engage in the notches of the peripheral notched wheel 77. It is now clear that the presser and compacter device 83 will be operated simultaneously with the operation of the conveyor. As shown in Fig. 2, the end of this presser device that is toward the hopper 73 is slightly above the edges of the conveyor. And the opposite end of the presser device 83 is below the side

edges of the conveyor. The lower portion of the presser device travels along with the conveyor and gradually and firmly presses and compacts the sand into the conveyor while the conveyor is carrying the sand toward the ramming head. The arrangement is such that a sufficient degree of pressure is applied to the sand to compress the sand into a hard and nearly solid mass.

The sand, being thus compressed and compacted in the conveyor, forms a practically solid bar of sand. This practically solid bar of sand is discharged from the conveyor into a chute 85, the walls of which are like the walls 70, 71 and 72 of the conveyor. This chute 85 opens through the wall 39 of the ramming head housing so that the compacted bar of sand is moved across the ramming head housing and into the path of the ramming head thrower or impeller member 49, etc., that is attached to the periphery of the wheel 48. The speed of operation of the mechanism is timed and regulated so that the ramming head thrower or impeller member 49, etc., at each revolution thereof cuts or takes from the bar of compacted sand a block, mass or section of said compacted sand having a length approximately equal to the width of said thrower or impeller member. Since the ramming head is rotated at great speed, this block, mass or section of compacted sand is thrown or slung from the ramming head through the chute opening from said ramming head (Fig. 5). The inclined wall 50 prevents adhesion of the sand to the impeller. The great speed and power at which the machine is operated causes these blocks, masses or sections of compacted sand to be thrown and flung at such great force as to be rammed solidly in the mold into which they are delivered.

This machine is used to ram the sand in the various molds by moving the machine along the track 3 to positions over the respective molds. While the supporting frame that operates along the track 3 is stationary the motor 14 is operated to move the intermediate or transversely movable carriage in directions transversely of the rails 3. During all of this movement the motor 53 is operating so as to operate the ramming head which receives the compacted blocks or masses of sand from the conveyor and rams said blocks or masses of compacted sand into the mold. When the machine crosses the mold and is ready for the return trip, the motor 27 is operated to move the upper carriage longitudinally along the intermediate transversely movable carriage. The upper carriage is moved a sufficient distance in this way so that during the return trip of the transversely movable carriage to its starting point, a layer or stratum of sand will be rammed into the mold alongside the first layer or stratum of sand that was put into the mold during the movement of the transversely movable car-

riage from its starting position. When the transversely movable carriage reaches its starting position the motor 14 is reversed to repeat the travel of said transversely movable carriage across the mold in opposite directions from and to the starting position. The motor 53 operates all the time and the motor 27 is operated intermittently or sufficiently to move the upper carriage longitudinally for the purposes described. Sand may be discharged into the feed hopper 73 by any appropriate means.

From the foregoing it is now clear that my improved ramming machine operates at great speed and differs from all prior ramming machines in highly important particulars. So far as I am informed, my ramming machine differs from all prior ramming machines in that the sand is compacted into a solid mass or bar before delivery into the ramming head; and this solid mass or bar of sand is moved endwise into the ramming head and blocks or masses of the solid bar of compacted sand are broken from said bar by the ramming head and are thrown or slung with great ramming force into the molds. By use of this machine two workmen to control the machine are able to perform the work that has heretofore required numerous workmen. Not only does the machine dispense with the services of numerous workmen, but it also performs the work in a much shorter period of time.

The degree of pressure on the sand in the conveyor may be increased or reduced, as desired. This variation is obtained by lowering one end of the compacting device in order to increase the pressure so as to compact the sand more solidly and by raising said end of the compacting device so as to reduce the pressure and thereby reduce the density or solidity of the compacted sand, as desired. As shown (Fig. 13), the ends of the supports 75^a that are toward the ramming head have attached thereto the upper ends of plates 86. The lower ends of said plates 86 are mounted on pivots 87 in connection with the supports 54 and are thereby supported for pivotal movements. The opposite ends of the supports 75^a have attached thereto the upper ends of plates 88, the lower ends of which have therein vertical slots 89. Bolts 90 project from the supports 54 through the slots 89 and have screwed thereon clamping nuts 91 which may be tightened to hold the support 75^a in any adjustment in which they are placed or loosened to permit the ends of the supports 75^a to be raised and lowered. Thus, the pressure upon the sand in the conveyor may be increased and reduced, as desired. By this means, the solidity and density of the bar of compacted sand may be increased and reduced.

It is now clear that the invention obtains

all of its intended objects in a highly efficient, satisfactory and economic manner. The construction, arrangement and relationship of the elements of the machine may be 5 widely varied without departure from the nature and principle of the invention. I do not restrict myself in unessential respects but what I claim and desire to secure by Letters Patent is:

10 1. A ramming machine comprising a rotary projector, mechanism for rotating said projector to project compacted sand centrifugally therefrom, and mechanism for compacting sand and delivering approximately 15 uniform blocks of said compacted sand to said projector at successive revolutions of said projector.

20 2. A ramming machine comprising a rotary projector, mechanism for rotating said projector to project compacted sand centrifugally therefrom, a conveyer for conveying sand to said projector, and mechanism for compacting the sand in said conveyer during the movement of the sand toward the projector.

25 3. A ramming machine comprising a rotary projector, mechanism for rotating said projector to project compacted sand centrifugally therefrom, a conveyer for conveying sand to said projector, mechanism for compacting the sand in said conveyer during the movement of the sand toward the projector, and means for varying the density to which the sand is compacted by said compacting 35 means.

40 4. A ramming machine comprising a rotary projector, mechanism for rotating said projector to project compacted sand centrifugally therefrom, mechanism for compacting and delivering compacted sand to said projector, a carriage for supporting and moving said projector and said mechanism over a mold into which the sand is to be projected, and mechanism supported by said carriage 45 for moving said carriage.

50 5. A ramming machine comprising a rotary projector, mechanism for rotating said projector to project compacted sand centrifugally therefrom, mechanism for compacting and delivering compacted sand to said projector, a carriage for supporting and moving said projector and said mechanism over a mold into which the sand is to be projected, and mechanism supported by said carriage 55 for moving said carriage alternately in opposite directions.

60 6. A ramming machine comprising a rotary projector, mechanism for rotating said projector to project compacted sand centrifugally therefrom, mechanism for compacting and delivering compacted sand to said projector, a carriage for supporting and moving said projector and said mechanism over a mold into which the sand is to be projected, mechanism supported by said car- 65

riage for moving said carriage alternately in opposite directions, and mechanism supported by said carriage for moving said carriage in a direction transversely of said first named movements of said carriage.

70 7. A ramming machine comprising a rotary projector, mechanism for rotating said projector to project compacted sand centrifugally therefrom, a conveyer for conveying sand to said projector, a carriage supporting said projector and said mechanism and said conveyer, mechanism for moving said carriage alternately in opposite directions over a mold in which the sand is to be compacted, and mechanism for moving said carriage in a direction at right angles to said first named movements of said carriage.

75 8. A ramming machine comprising a rotary projector, devices for compacting and conveying sand to said projector, a motor, and mechanism for operating said devices and said projector by said motor.

80 9. A ramming machine comprising a rotary projector, an endless conveyer for conveying sand to said projector, means for tensioning said conveyer, a hopper opening into said conveyer for discharging sand into said conveyer, a shaft supporting said projector, a motor for rotating said shaft, connections operated by said shaft for operating said conveyer, and means for compacting the sand into said conveyer during movement of said conveyer and the sand carried thereby toward said projector.

90 10. A ramming machine comprising a rotary projector, and endless conveyer for conveying sand to said projector, means for tensioning said conveyer, a hopper opening into said conveyer for discharging sand into said conveyer, a shaft supporting said projector, a motor for rotating said shaft, connections operated by said shaft for operating said conveyer, and means for compacting the sand into said conveyer automatically and as an incident to the movement of said sand toward said projector by said conveyer.

105 11. A ramming machine comprising a rotary projector, an endless conveyer for conveying sand to said projector, means for tensioning said conveyer, a hopper opening into said conveyer for discharging sand into said conveyer, a shaft supporting said projector, a motor for rotating said shaft, connections operated by said shaft for operating said conveyer, means for compacting the sand into said conveyer automatically and as an incident to the movement of said sand toward said projector by said conveyer, and means for varying the density to which the sand is compacted in said conveyer.

115 12. A ramming machine comprising a truck movable longitudinally, a carriage mounted on said truck for movements transversely of said truck, mechanism for moving said carriage alternately in opposite direc- 120
125
130

- tions transversely of said truck, a rotary projector, means for supporting said projector by said carriage, and mechanism for operating said projector.
13. A ramming machine comprising a truck movable longitudinally, a carriage mounted on said truck for movements transversely of said truck, mechanism for moving said carriage alternately in opposite directions transversely of said truck, a rotary projector, means for supporting said projector by said carriage, mechanism for operating said projector, and a conveyer supported by said carriage for conveying sand to said projector.
14. A ramming machine comprising a truck movable longitudinally, a carriage mounted on said truck for movements transversely of said truck, mechanism for moving said carriage alternately in opposite directions transversely of said truck, a rotary projector, means for supporting said projector by said carriage, mechanism for operating said projector, a conveyer supported by said carriage for conveying sand to said projector, and mechanism for compacting the sand in said conveyer during the movement of said sand toward said projector.
15. A ramming machine comprising a longitudinally movable truck, a carriage supported on said truck for movements transversely of said truck, mechanism for moving said carriage alternately in opposite directions transversely of said truck, an upper carriage supported by said first carriage for movements transversely of the movements of said first carriage, and a rotary projector supported by said upper carriage.
16. A ramming machine comprising a longitudinally movable truck, a carriage supported on said truck for movements transversely of said truck, mechanism for moving said carriage alternately in opposite directions transversely of said truck, an upper carriage supported by said first carriage for movements transversely of the movements of said first carriage, a rotary projector supported by said upper carriage, and a conveyer supported by said upper carriage for conveying sand to said projector.
17. A ramming machine comprising a longitudinally movable truck, a carriage supported on said truck for movements transversely of said truck, mechanism for moving said carriage alternately in opposite directions transversely of said truck, an upper carriage supported by said first carriage for movements transversely of the movements of said first carriage, a rotary projector supported by said upper carriage, a conveyer supported by said upper carriage for conveying sand to said projector, and means supported by said upper carriage for delivering sand into said conveyer.
18. A ramming machine comprising a transversely movable carriage, mechanism for moving said carriage alternately in opposite directions, an upper carriage supported on said first carriage for movements at right angles to the transverse movements of said first carriage, mechanism for moving said upper carriage, a rotary projector supported by said upper carriage, and mechanism supported by said upper carriage for operating said projector.
19. A ramming machine comprising a transversely movable carriage, mechanism for moving said carriage alternately in opposite directions, an upper carriage supported on said first carriage for movements at right angles to the transverse movements of said first carriage, mechanism for moving said upper carriage, a rotary projector supported by said upper carriage, mechanism supported by said upper carriage for operating said projector, and a conveyer supported by said upper carriage for conveying sand to said projector.
20. A ramming machine comprising a transversely movable carriage, mechanism for moving said carriage alternately in opposite directions, an upper carriage supported on said first carriage for movements at right angles to the transverse movements of said first carriage, mechanism for moving said upper carriage, a rotary projector supported by said upper carriage, mechanism supported by said upper carriage for operating said projector, a conveyor supported by said upper carriage for conveying sand to said projector, and a device supported by said upper carriage for compacting sand in said conveyer.
21. A ramming machine comprising a rotary centrifugal projector, mechanism for rotating said projector to project compacted sand centrifugally therefrom, means for guiding the discharge of the sand from said projector, mechanism for compacting and delivering sand to said projector, and means for varying the density to which the sand is compacted.
22. A ramming machine comprising a rotary projector, a shaft for rotating said projector, a conveyer for conveying sand to said projector, connections for operating said conveyer by said shaft, a device for compacting the sand in said conveyer, and means for operating said device by said shaft.
23. A ramming machine comprising a rotary projector, a shaft for rotating said projector, a conveyer for conveying sand to said projector, connections for operating said conveyer by said shaft, a device for compacting the sand in said conveyer, means for operating said device by said shaft, and means for supporting said device in different positions for operation to vary the density in which the device will compact the sand in said conveyer.

24. A ramming machine comprising a rotary projector, mechanism for rotating said projector to project sand centrifugally therefrom, a rigid chute for guiding compacted sand to said projector, a conveyer for discharging sand into said chute, means for operating said conveyer by said mechanism, and a device for compacting the sand in said conveyer during the movement of the sand toward the projector.

25. In a ramming machine, a projector, mechanism for compacting sand and delivering the compacted sand to the projector, and a device for delivering uncompacted sand to said mechanism to be compacted and conveyed thereby to the projector.

26. In a ramming machine, a projector, mechanism for compacting sand and delivering the compacted sand to the projector, a device for delivering uncompacted sand to said mechanism to be compacted and conveyed thereby to the projector, a carriage supporting said projector and said mechanism, and means for moving said carriage simultaneously with the operation of said projector and said mechanism.

27. In a machine of the character described, a channel conveyer for conveying sand to be rammed, a projector for ramming the sand delivered thereto from said conveyer, mechanism for operating said conveyer and said projector simultaneously, and a device for compressing the sand in said conveyer.

28. A ramming machine comprising a projector, a stationary chute for conducting sand to the projector, an endless series of channel members forming the conveyer for conveying sand to said chute, means for delivering sand into said conveyer, and means for compressing and compacting the sand in said conveyer during movement of the sand toward said projector.

29. A machine of the character described comprising a support, a carriage mounted on said support for transverse movements, mechanism for moving said carriage transversely across said support, an upper carriage mounted on said first carriage and movable transversely with said first carriage, mechanism for moving said upper carriage in a direction angularly with respect to the direction of movement of said first carriage, projecting mechanism supported by said upper carriage, and means for operating said projecting mechanism.

30. A machine of the character described comprising a support, a carriage mounted on said support for transverse movements, mechanism for moving said carriage transversely across said support, an upper carriage mounted on said first carriage and movable transversely with said first carriage, mechanism for moving said upper carriage in a direction angularly with respect to the

direction of movement of said first carriage, projecting mechanism supported by said upper carriage, and means for operating said projecting mechanism whether said first carriage be in motion or stationary.

70

31. A machine of the character described comprising a projector, a conveyer for conveying sand to said projector, a carriage supporting said projector and said conveyer, and mechanisms for moving said carriage both transversely and longitudinally.

75

32. A machine of the character described comprising a rotary projector, a conveyer for conveying sand to said projector, a motor, mechanism operated by said motor for operating said projector and said conveyer simultaneously, means for compacting the sand in said conveyer to varying degrees of density as desired, and mechanism for operating said projector and said conveyer and said compacting means.

80

33. A ramming machine comprising a transversely movable carriage, mechanism for moving said carriage transversely in opposite directions, a longitudinally movable carriage supported on said transversely movable carriage, mechanism for moving said longitudinally movable carriage longitudinally on said transversely movable carriage in directions transversely of the movements of said transversely movable carriage, a centrifugal projector supported by said longitudinally movable carriage, mechanism for delivering sand to said projector, and mechanism for operating said projector and said last named mechanism.

90

34. A ramming machine comprising a transversely movable carriage, mechanism for moving said carriage transversely in opposite directions, a longitudinally movable carriage supported on said transversely movable carriage, mechanism for moving said longitudinally movable carriage longitudinally on said transversely movable carriage in directions transversely of the movements of said transversely movable carriage, a centrifugal projector supported by said longitudinally movable carriage, mechanism for delivering sand to said projector, and mechanism for operating said projector and said last named mechanism whether said transversely movable carriage be in motion or stationary.

105

35. A machine of the character described comprising a transversely movable carriage, devices for moving said transversely movable carriage transversely in opposite directions, a longitudinally movable carriage supported by said transversely movable carriage, devices for moving said longitudinally movable carriage longitudinally in the direction transversely of the movements of said transversely movable carriage, a projector supported by said longitudinally movable carriage, a conveyer supported by said longitudinally movable carriage, means for delivering sand into

said conveyer, and mechanism supported by said longitudinally movable carriage for operating said projector and said conveyer.

36. A machine of the character described comprising a transversely movable carriage, devices for moving said transversely movable carriage transversely in opposite directions, a longitudinally movable carriage supported by said transversely movable carriage, devices

10 for moving said longitudinally movable carriage longitudinally in the direction transversely of the movements of said transversely movable carriage, a projector supported by said longitudinally movable carriage, a conveyer supported by said longitudinally movable carriage, means for delivering sand into

15 said conveyer, mechanism supported by said longitudinally movable carriage for operating said projector and said conveyer, and a device supported by said longitudinally movable carriage for compacting the sand in said conveyer automatically and as an incident to movement of said conveyer toward said projector.

20 37. A machine of the character described comprising an endless series of pivotally connected channel conveyer sections, wheels for supporting and operating said sections in a relationship in which the sections that are

25 between the wheels are in endwise abutting contact, means for preventing the conveyer formed by said sections from bending between said wheels, mechanism for rotating one of said wheels to operate said conveyer,

30 and a rotary projector rotating on an axis parallel with the plane of movement of said conveyer.

35 38. A machine of the character described comprising an endless series of pivotally connected channel conveyer sections, wheels for supporting and operating said sections in a relationship in which the sections that are between the wheels are in endwise abutting contact, mechanism for rotating one of said wheels to operate said conveyer, means

40 for preventing the conveyer formed by said sections from bending between said wheels, a rotary projector rotating on an axis parallel with the plane of movement of said conveyer, and a stationary chute for conveying material from said conveyer to said projector.

45 39. In a ramming machine, a conveyer composed of a series of pivotally connected channel conveyer sections, wheels for supporting said conveyer, mechanism for rotating one of said wheels to operate said conveyer, and a compressor for compressing material in the conveyer during movement

50 of said conveyer toward one of said wheels.

40. In a ramming machine, a conveyer composed of a series of pivotally connected channel conveyer sections, wheels for supporting said conveyer, mechanism for rotating one of said wheels to operate said con-

veyer, a compressor for compressing material in the conveyer, a chute for receiving the material discharged from the conveyer, and a rotary projector for receiving the material from said chute.

70 41. A ramming machine comprising a centrifugal projector, a housing in which said projector is enclosed, means forming a chute from said housing, a chute opening into said housing, a channel conveyer for discharging material into said last named chute, mechanism for operating said conveyer, and a compressor for compressing the material in said conveyer during movement of the material toward said projector.

75 42. In a ramming machine, a longitudinally movable carriage, mechanism for moving said carriage longitudinally in opposite directions, a conveyer supported by said carriage, mechanism for operating said conveyer parallel with the direction in which said carriage is moved longitudinally, and mechanism for compacting material in said conveyer during movement of said material by said conveyer.

80 43. In a ramming machine, a longitudinally movable carriage, mechanism for moving said carriage longitudinally in opposite directions, a conveyer supported by said carriage, mechanism for operating said conveyer parallel with the direction in which said carriage is moved longitudinally, mechanism for compacting material in said conveyer, a projector beyond said conveyer, and means for conducting compacted material from said 100 conveyer to said projector.

85 44. In a ramming machine, a transversely movable carriage, a conveyer supported by said carriage, mechanism for moving said conveyer longitudinally in said carriage and transversely of the direction of movement of said carriage, a device for receiving material from said conveyer, and means for compacting the material in said conveyer during movement of said material by said conveyer.

90 45. In a ramming machine, an endless conveyer, means for delivering sand into said conveyer, an endless compacting device for compacting the sand in said conveyer, and mechanisms for operating said conveyer and said compacting means in directions in which adjacent portions of said conveyer and said compacting means move in the same direction.

95 46. In a ramming machine, an endless conveyer, a means for delivering sand into said conveyer, an endless compacting device for compacting the sand in said conveyer, mechanisms for operating said conveyer and said compacting means in directions in which adjacent portions of said conveyer and said compacting means move in the same direction, and devices for supporting said compacting means in different adjustments for operation.

47. In a ramming machine, an endless conveyer, means for delivering sand into said conveyer, an endless compacting device for compacting the sand in said conveyer, mechanisms for operating said conveyer and said compacting means in directions in which adjacent portions of said conveyer and said compacting means move in the same direction, devices for supporting said compacting means in different adjustments for operation, a rotary projector, and means for conducting the compacted material from said conveyer to said projector.

48. In a ramming machine, the combination of a centrifugal projector, a chute for conducting compacted sand to said projector, and mechanism for compacting and delivering compacted sand to said chute.

49. In a ramming machine, a carriage, a centrifugal projector supported by said carriage, and mechanism supported by said carriage for compacting and delivering compacted sand to said projector in any of the positions of said carriage.

50. In a ramming machine, a carriage, a centrifugal projector supported by said carriage, mechanism supported by said carriage for compacting and delivering compacted sand to said projector in any of the positions of said carriage, and mechanisms for moving said carriage to different lateral and longitudinal positions.

51. In a ramming machine, a laterally and longitudinally movable carriage, mechanisms for moving said carriage laterally and longitudinally, a projector supported by said carriage, and mechanism for operating said projector whether said carriage be in motion or stationary.

52. In a ramming machine, a laterally and longitudinally movable carriage, mechanisms for moving said carriage laterally and longitudinally, a projector supported by said carriage, mechanism for operating said projector whether said carriage be in motion or stationary, and mechanism for compacting and delivering sand to said projector.

53. A ramming machine comprising an endless conveyer, mechanism for tensioning said conveyer, mechanism for compacting sand in said conveyer during operation of said conveyer, a centrifugal projector, and means for conducting the compacted sand from said conveyer to said projector.

54. In a ramming machine, a transversely and longitudinally movable carriage, mechanisms for moving said carriage transversely and longitudinally, a projector supported by said carriage, a conveyer supported by said carriage, means for conducting sand from said conveyer to said projector, and mechanism for operating said projector and said conveyer.

55. In a ramming machine, a transversely and longitudinally movable carriage, mecha-

nisms for moving said carriage transversely and longitudinally, a projector supported by said carriage, a conveyer supported by said carriage, means for conducting sand from said conveyer to said projector, mechanism for operating said projector and said conveyer, and mechanism for compacting the sand in said conveyer while the sand is being conveyed toward said projector.

56. In a ramming machine, a longitudinally movable conveyer, a compacting device supported above said conveyer for compacting sand in said conveyer, mechanism for operating said conveyer and said compacting device simultaneously, and mechanism for supporting said compacting device in different adjusted positions for operation.

57. In a ramming machine, a longitudinally movable conveyer, a compacting device supported above said conveyer for compacting sand in said conveyer, mechanism for operating said conveyer and said compacting device simultaneously, mechanism for supporting said compacting device in different adjusted positions for operation, a centrifugal projector, and mechanism for conducting the compacted sand from said conveyer to said projector.

58. In a ramming machine, a projector comprising a shaft, a wheel attached to said shaft, a stationary housing enclosing said wheel, a chute opening from one side of said housing, a scoop attached to the periphery of said wheel for projecting material centrifugally through said chute, a chute opening into said housing for discharging material into said housing across the periphery of said wheel, a conveyer, means for operating said conveyer to discharge material into said chute, and mechanism for compacting the material in said conveyer during movement of said material toward said chute.

59. A ramming machine comprising a transversely and longitudinally movable carriage, mechanism for moving said carriage transversely and longitudinally as desired, a projector supported by said carriage, a conveyer supported by said carriage, a hopper supported by said carriage for discharging sand into said conveyer, and mechanism for operating said projector and said conveyer.

60. A ramming machine comprising a transversely and longitudinally movable carriage, mechanism for moving said carriage transversely and longitudinally as desired, a projector supported by said carriage, a conveyer supported by said carriage, a hopper supported by said carriage for discharging sand into said conveyer, mechanism for operating said projector and said conveyer, a chute for conducting sand from said conveyer to said projector, and means for compacting the sand in said conveyer during movement of said sand toward said chute.

61. A ramming machine comprising a cen-

- trifugal projector, a chute for delivering sand to said projector, mechanism for compacting and delivering sand into said chute, and means for varying the density at which the sand is compacted.
- 5 62. A ramming machine comprising a centrifugal projector, mechanism for moving said projector longitudinally and laterally to different positions for operation, and mechanism for compacting and delivering the compacted sand to said projector.
- 10 63. A ramming machine comprising a centrifugal projector, mechanism for moving said projector longitudinally and laterally to different positions for operation, mechanism for compacting and delivering the compacted sand to said projector, and means for varying the density at which the sand is compacted.
- 15 64. A conveyor for a sand slug machine comprising a series of links each having a trough-shaped body portion and lug structure projecting from the ends of each link beneath its body portion and towards the adjacent links, the lug structure on one link comprising widely spaced elements receiving between them the lug structure projecting from the adjacent link, and an element pivotally connecting said juxtaposed lug structure.
- 20 65. A conveyor for a sand slug machine comprising a series of links each having a trough-shaped body portion and lug structure projecting from the ends of each link beneath its body portion and towards the adjacent links, the lug structure on one link comprising widely spaced elements receiving between them the lug structure projecting from the adjacent link, an element pivotally connecting said juxtaposed lug structure, and a roller surrounding each of said elements for supporting the links on a carrier member.
- 25 66. In a sand slug machine, a conveyor device comprising two series of pivotally connected links arranged so as to oppose each other and compress a quantity of sand between them, there being rollers on said links, and an individual rigid member for each of said series over which the rollers on that series travel.
- 30 67. In a sand slug machine, opposing conveyor devices for compressing a mass of sand to form a bar, a stationary element beyond the discharge end of said devices for supporting the discharge end of the bar conveyed thereby, and a hammer-like member with driving mechanism for separating a portion of said bar from the body thereof and discharging it under high momentum from the machine.

ANDREW F. HOWE.
